UNITED STATES PATENT OFFICE.

JESSE A. MITCHELL, OF JASPER, FLORIDA.

BOOKSTAND.

Application filed June 4, 1925. Serial No. 34,893.

My invention relates to improvements in book stands particularly intended for supporting large, heavy and otherwise unwieldy books, charts, etc., in position to make copies therefrom; entries therein or thereon and for other purposes, my principal object being to provide a stand capable of various adjustments whereby a book, chart or the like positioned thereon may be moved quickly and easily to different positions for the convenience of a person using the same.

In addition it is my object to provide an adjustable guide device for following the lines of the pages of a book supported on the stand and to provide a simple, efficient, conveniently manipulated step by step operating means for said guide device.

Further, it is my object to provide a book stand embodying the aforementioned beneficial features which is cheap and easy to produce, strong, durable and thoroughly reliable and efficient in use.

With the foregoing and other objects in view, my invention consists in the novel features of construction, combination and arrangement of parts as will be herein-after more fully described, illustrated in the accompanying drawings and defined in the appended claims.

In the drawings, wherein like characters of reference denote corresponding parts in the different views:—

Fig. 1 is a front elevation of a book stand embodying the novel and essential features of my invention, a book being shown supported on said stand;

Fig. 2, an end view of the stand;

Fig. 3, an enlarged end view of the sliding carriage;

Fig. 4, an enlarged front view of the sliding carriage;

Fig. 5, an enlarged section on the line 5—5 of Fig. 4;

Fig. 6, an enlarged top plan of a portion of the tiltable support for the sliding carriage;

Fig. 7, an enlarged perspective, with parts broken away, of a portion of the step by step operating mechanism for the line guide device;

Fig. 8, an enlarged detail perspective showing the cooperating pawls of the line guide device and the manner in which the latter is mounted for adjustments thereof;

Fig. 9, a detail view showing a means which may be employed to positively lock the line guide device in certain of its adjusted positions;

Fig. 10, an enlarged detail view showing the manner in which the sliding carriage is connected to its tiltable support; and

Fig. 11, an enlarged detail section on the line 11—11 of Fig. 2.

Referring to the drawings in detail, 10—10 designates a pair of hollow supporting standards rigidly connected together in spaced relation in any suitable manner as, for example, by a cross piece or pieces 11 and a box 12, the latter serving as a storage compartment. Foot pieces 10'—10' are provided at the lower ends of said standards and carried by these foot pieces are casters 10^a whereby the stand 75 as an entirety may readily be moved over the floor to any position desired.

Vertically slideable within the standards 10—10 are bars 13—13, respectively, provided along their rear faces with rack teeth 14 engaged by pinions 15 on a horizontal shaft 16 journaled in suitable bearings on the standards 10—10 whereby rotation of said shaft will raise or lower said bars as is apparent. A conventional ratchet device indicated generally at 17 is provided on shaft 16 for rotating the same.

Projecting forwardly from the front faces of the bars 13—13 at their upper ends are extensions 18 formed either as integral parts of said bars or, as herein shown, as separate parts in the form of blocks bolted to said bars, the standards 10—10 being slotted in their front walls at their upper ends as at 19 to receive said extensions whereby the latter are prevented from interfering with vertical movements of the bars within the standards.

Rack bars 20—20 are pivoted as at 21 to the upper ends of the bars 13—13, respectively, and projecting from said rack bars are slotted arms 22—22, respectively, which lie against the inner faces of the extensions 18—18, respectively, and have bolts carried by said extensions passing therethrough and equipped with thumb nuts 23 whereby said arms may be clamped against said extensions to secure the rack bars either in horizontal position or in different positions inclined to the horizontal, said rack bars extending fore and aft with respect to the stand and being tiltable.

in the manner indicated for a purpose which will presently appear.

A support A for a slidable book rack is mounted on the rack bars 20—20 for fore and aft movement along the latter, said support consisting of a pair of uprights 24—24, one above each rack bar, connected together by longitudinal spacing and bracing rails 25 and having projecting forwardly from their front faces, at their lower ends, a platform 26 carrying a pair of longitudinally extending track rails 27—27 formed preferably of angle iron. Carried by the uprights 13—13 and by the platform 26, are pinions 28 and 29, respectively, which mesh with the teeth of the rack bars 20—20, respectively, and serve as rollers mounting the book rack support on the bars 13 for movement along the same. The front pair of pinions, 29—29, are mounted on a shaft 30 journaled in suitable bearings 31 on the platform 26, and a conventional ratchet device 32 is provided on said shaft for rotating the same thereby to effect rotation of said pinions to cause the book rack support to be moved forwardly or rearwardly to any position desired along the rack bars 20—20.

In order to hold the support A against upward movement away from the rack bars 20—20 and to guide same in its movement along said rack bars, rollers 33 are mounted in suitable brackets 34 projecting from the support and are engaged with the under faces of side flanges 35 of the respective rack bars, the brackets 34 preferably including adjustable bearings as shown for the shafts of the rollers 33 whereby the latter may be adjusted to take up any play between the pinions 28—29 and the rack bars 20—20 and thus maintain a free running yet firm assembly of the support with said rack bars.

A book rack B is mounted on the support A for sliding movement along the same, said rack consisting of a vertical, preferably elongated rectangular frame portion composed of upper, lower and intermediate longitudinally extending strips or bars 36 connected by vertical strips or bars 37, and an elongated substantially horizontal platform portion 38 extending forwardly from the lower part of said vertical portion. On the under side of said platform portion are two or more blocks 39 carrying rollers 40 which rest on the angle-iron track rails 27—27 and thus support the rack B as an entirety for free longitudinal movement along said rails, a knob or other suitable form of thumb grip device 41 being provided on the front of the platform portion 38 to facilitate such movements. Preferably the rack B normally is inclined rearwardly and is arranged to rest against and slide along the rails 25 of the support A.

The platform portion 38 of the rack B is adapted to serve as a support for the

lower edge of a book while the vertical frame portion composed of the strips 36 and 37 is adapted to serve as a support for the front and back covers and the pages of the book, and when a book is thus placed on said rack, as shown in Fig. 1, it is manifest that by reason of the structural arrangement thus far described the rack B, and consequently any book supported thereon, may be adjusted vertically, tilted up or down, moved forwardly or rearwardly and also moved longitudinally.

At each end of the rack B I provide a device for following the lines of the pages of a book that may be supported on said rack, either for copying or for other purposes. These devices are right and left hand, respectively, but in all other respects are duplicates of one another, so that only one will be described in detail. It consists of three bars 42—43—44 rectangular in cross section and arranged side by side in abutting relation, the two outside bars 42—44 having teeth 45 formed along their front edges, while the front edge of the middle bar 43 is smooth and lies normally inward with respect to the teeth of the outside bars. These bars, collectively, are formed near their upper and lower ends with circular bosses 46 received within circular bearing members 47 at the free ends of a pair of bracket arms 48 projecting forwardly from upper and lower portions of the rack B, said bars thus being attached to said rack for collective rotation (see Fig. 7). Two of said bars, 43 and 44, are adapted to be moved longitudinally while the other, 42, is adapted to be held against longitudinal movement, this being effected by a pair of collars 49 affixed to bar 42 and engaging the respective bearing members 47.

One of these collars, the lowermost one, has an arm 50 extending therefrom towards the front of the platform 38, and engaged in a slot 51 in the free end of said arm is a pin 52 at one end of a rod 53 that is journaled for longitudinal sliding movement in suitable bearings 54 on the front of said platform, so that by shifting said rod rotation is imparted through the arm 50, to the bars 42—43—44. Rod 53 extends to a point near the middle of the platform 38 and is there provided with a suitable handle or other form of hand grip device 55 to facilitate shifting of the same.

Rotatably journaled in the bearings 54 on the front of the platform 38 is a pair of rods 56, 57 having angular extensions 58, 59, respectively, projecting towards the lower ends of the bars 43, 44, respectively. The said lower ends of said bars are formed with spaced flanges 60—60, 61—61, respectively between which the free ends of the respective extensions 58, 59 are received, so that by rotating either of said rods 56 or 57

its associated bar 43 or 44, as the case may be, is moved longitudinally. The spaced flange connections between the bars 43, 44 and the extensions 58, 59, respectively, are for the purpose of permitting rotation of the bars 42—43—44 collectively as aforementioned while maintaining connections between the extensions 58, 59 and the bars 43—44 whereby said bars may be moved longitudinally. The rods 56, 57, like rod 53, are extended to a point near the middle of the platform 38 and are there provided with handles or other suitable forms of hand grip devices 62 for effecting their rotation.

15 The fixed bar 42 carries one or more pins 63 engaged in an inclined slot or slots 64, as the case may be, in the middle bar 43 so that when said middle bar is moved longitudinally in one direction, upwardly in this instance, it is caused to be moved forwardly until its front smooth face comes flush with or slightly beyond the teeth of the bars 42—44, and when it is moved in the opposite direction it is caused to recede to its normal position with its front smooth face behind said teeth.

A sleeve 65 snugly embraces the bars 42—43 and 44 and is slidable along the same, said sleeve having projecting from the front thereof a pair of spaced flanges 66 between which are pivoted two pawls 67 and 68, the former for cooperation with the teeth of fixed bar 42 and the latter for cooperation with the teeth of longitudinally movable bar 44. Each pawl includes a portion overlying the smooth front face of middle bar 43. A spring or springs 69 holds said pawls yieldably in engagement with the teeth of the bars 42—44.

40 On a suitable bracket 70 at the top of the book rack B is mounted a conventional spring drum 71 having wound thereon a cord or tape 72 that is connected at its free end with a pin 73 projecting from one of the flanges 66 of sleeve 65, the function of said drum being to urge said sleeve normally towards its uppermost limit of sliding movement along the bars 42—43—44, this operation occurring whenever the middle bar 43 is projected outward to engage the overlying portions of the pawls 67, 68 and disengage them from the teeth 45 of the bars 42 and 44. When the pawls are engaged with the teeth 45, drum 71 exerts through the cord or tape 72 an upward pull on the sleeve 65 which pull cooperates with said pawls to hold said sleeve in any position to which it may be moved along the bars 42—43—44, it being observed that sleeve 65 is movable down the bars 42—43—44 in a step by step manner merely by reciprocating bar 44, the action being as follows: A downward movement of bar 44 as effected by rod 57 forces pawl 68 and consequently the sleeve 65 downward, pawl 67 at the same

time riding over a tooth on fixed bar 42, while upon upward movement of bar 44 its teeth ride over pawl 68 and pawl 67 acts to hold said sleeve against upward movement. Thus, merely by rocking the handle 62 of rod 57 the sleeve 65 may be caused to move step by step down the bars, while merely by rocking the handle of rod 56 bar 43 may be projected to disengage the pawls from the teeth of bars 42—44 and the drum 71 then will act to draw the sleeve entirely to the top of the bars in position to again be moved in step by step fashion down the same.

On the inner face of sleeve 65 are grooves 74 within which is mounted for fore and aft sliding movement a plate 75, having pivoted thereto as at 76 for vertical swinging movement a line guide rule or strip 77, a thumb nut 78 being provided to secure said rule or strip in any vertically swung position to which it may be adjusted. The step by step movement of sleeve 65 along the bars 42—43 and 44 is for the manifest purpose of moving the rule or strip 77 90 downward to follow succeeding lines of a page of a book supported on the rack B, while the fore and aft adjustment of said rule permitted by reason of the sliding connection of plate 75 with the grooves 74 is 95 for the purpose of accommodating the rule or strip to books of different thicknesses. If for any reason the lines of the book pages do not extend truly horizontally when the book is positioned on the rack B the rule 100 may then be swung about its pivot 76 parallel to the lines. When it is desired to turn a page of the book, rod 53 is shifted to rotate the bars 42—43—44 and thus swing the rule or strip 77 outwardly to a position 105 where it will not interfere with turning of the book pages.

The frictional engagement between plate 75 and the grooves 74 is sufficient under most conditions to maintain any fore and aft adjustment of the rule or strip 77, but if desired I may employ a positive lock for said plate to hold it in adjusted position. Such a lock is illustrated in Fig. 9 and consists of a pin 79 mounted for vertical movement in guides 80 carried by the sleeve 65, said pin normally being urged upward by a spring 81 and having at its lower end a lateral extension 82 adapted for engagement with any one of a number of teeth 83 formed 110 along the lower edge of plate 75. Merely by pressing downward on this pin the lateral extension 82 may be disengaged from any given tooth and the plate 75 may then be moved fore or aft as desired, and then by 115 releasing the pressure on said pin it will spring upward and bring the lateral extension 82 into engagement with another tooth, thereby locking the plate against further 120 sliding movement.

From the foregoing description considered in connection with the accompanying drawings it is believed that the construction, operation and advantages of my improvements will be fully understood. It is desired to point out, however, that various changes and desirable additions may be made in and to the structure shown within the spirit and scope of my invention as defined in the appended claims.

I claim:

1. In a book stand, a book rack, a line guide rule, means in the form of a plurality of toothed bars for moving said rule step by step, said rule being carried by said bars, and means for rotating said bars to swing said rule away from the rack to permit the pages of a book supported thereon to be turned.
2. In a book stand, a book rack, a pair of toothed bars carried by said rack, one of said bars being immovable longitudinally and the other being reciprocable, a sleeve around said bars, a pair of pawls carried by said sleeve cooperating with the teeth of said bars, respectively, whereby reciprocation of said reciprocable bar causes said sleeve to be moved step by step along said bars, a line guide rule carried by said sleeve,
3. a third bar between said first mentioned

bars, said pawls overlying said third bar, means for moving said third bar to disengage said pawls from the teeth of said first mentioned bars, and means operating when said third bar is so moved to shift said sleeve along said bars.

3. In a book stand, a book rack, a pair of toothed bars carried at one end of said rack, one of said bars being immovable longitudinally and the other being reciprocable, a sleeve around said bars, a pair of pawls carried by said sleeve cooperating with the teeth of said bars, respectively, whereby reciprocation of said reciprocable bar causes said sleeve to be moved step by step along said bars, a line guide rule carried by said sleeve, a third bar between said first mentioned bars, said pawls overlying said third bar, a pin and slot connection between said longitudinally immovable bar and said last mentioned bar whereby longitudinal movement of the latter causes the same to be projected laterally to disengage said pawls from the teeth of said first mentioned bars, and means operating when said pawls are disengaged from the teeth of said toothed bars to shift said sleeve along said bars.

In testimony whereof I hereunto affix my signature.

JESSE A. MITCHELL.
